UNITED STATES PATENT OFFICE.

HAYWARD J. SMALL, OF CLARKSBURG, WEST VIRGINIA.

OIL AND GAS WELL SWAB.

Application filed June 13, 1927. Serial No. 198,587.

This invention relates to improvements in oil and gas well swabs, and more particularly to a swab which may be lowered in a well casing with entire freedom despite the various obstructions common in long strings of casing and tubing in bored wells, and which may be expanded, when desired, to lift the fluid from the well casing.

An object of the invention is to provide on oil and gas well fluid swab which will be provided with a tapered stem on which the rubber swab is slidably mounted, and the further provision of an adjustable collar on said stem to limit the movement of said swab and consequently limit the desired degree of expansion of the swab.

A further object of the invention is to provide an oil and gas well fluid swab which will be mounted on a hollow tapered stem, thereby permitting the fluid to pass upward through said stem as the swab is lowered in a well casing, and the swab caused to be expanded upon an upward movement of the stem, to force the fluid from the well casing.

Other objects will appear as the description proceeds.

In the accompanying drawings, which form a part of my application:

Fig. 1 is a vertical sectional view through my improved swab showing the same in relaxed position within a well casing;

Fig. 2 is a vertical sectional view through the swab showing the same in expanded position;

Fig. 3 is a sectional view taken on the line 3-3 of Fig. 1; and

Fig. 4 is a sectional view taken on the line 4-4 of Fig. 2.

Like characters of reference are used throughout the following specification and the accompanying drawings to designate corresponding parts.

I have illustrated my improved swab in relaxed and expanded position within a well casing 1. A tapered stem 2, the base of which is always the lower end, is provided with a longitudinally extending fluid passage 3, and is threaded at its upper end 4 and lower end 5. A check valve 6 is positioned adjacent the upper end of the stem 2 and controls the flow of fluid through the stem as the swab is lowered in the well casing 1. The movable weighted collar 7 is slidably mounted on the stem below the

check valve 6, while an adjustable collar 8 having a double-diametered bore, is mounted on the stem adjacent the lower end thereof, and is held in the desired position, by means of a lock nut 9.

Interposed between the movable collar 7 and the adjustable collar 8, and slidably mounted on the tapered stem 2, is an expandable rubber swab 10, which, when relaxed, is slightly smaller in diameter than the bore of the well casing 1. It will be understood that the swab and stem will be attached to a weight or sinker (not illustrated.)

The mode of operation of my fluid swab is as follows: The rubber swab is slipped over the tapered stem until it expands sufficiently to provide a tight fit against the inner wall of the well casing 1. The lock nut 9 is then tightened until the adjustable collar 8 contacts with the lower end of the rubber swab 10. After this the swab is moved to its highest point on the tapered stem 1 or until it is relaxed to its normal position (Fig. 1). The swab is then ready to be lowered into the well by means of a cable and drum. As the swab is lowered into the fluid in the well, the fluid passes through the fluid passage in the stem and by the check valve 6. When it is desired to raise the swab, the stem is pulled upwardly, thereby closing the check valve, and the pressure of the fluid upon the top of the weighted collar 7 and the rubber swab causes them to slide down on the tapered shank and through the internal expansion due to the enlarged end of the shank distending the swab and also the compressive action from the fluid and the weighted collar, the swab is caused to snugly engage the walls of the well casing. Further lifting of the swab and the fluid entrapped thereabove consequently causes the forcing of the fluid from the casing.

Many minor changes in detail of construction may be resorted to without departure from the spirit of the invention.

I claim:

1. An oil or gas well swab, comprising a longitudinally bored stem of substantially uniform external diameter from its upper end to a point between its ends and of increasing diameter from said point toward its lower end, a substantially cylindrical compressible plug having an axial bore

- through which said stem is longitudinally slidabile, a collar secured to said stem adjacent its lower end of the plug when said stem is moved longitudinally upward 5 through said plug, a sleeve of smaller external diameter than said plug freely slidabile on the first named portion of said stem and resting directly on the upper end of said plug, and means on said stem above 10 said sleeve for limiting the movement of said sleeve toward the upper end of the stem when said stem is moved longitudinally downward through said plug.
2. An oil or gas well swab according to 15 claim 1 wherein the upper end of the collar and the lower end of the sleeve are concave.
3. An oil or gas well swab comprising a longitudinally bored stem of uniform diameter from its upper end to a point between its ends and tapering from its lower end to said point, a collar secured to the upper end of said stem, a second collar secured to said stem adjacent its lower end, a substantially cylindrical compressible plug 20 25 freely slidabile on said stem below said upper collar and expanded by the entry therein of the tapered portion of said stem when said stem is moved upwardly therethrough, and a weight freely movable on the first named portion of said stem and resting on 30 said plug.

In testimony whereof I have hereunto set my hand.

HAYWARD J. SMALL.

CERTIFICATE OF CORRECTION.

Patent No. 1,724,736.

Granted August 13, 1929, to

HAYWARD J. SMALL.

It is hereby certified that error appears in the printed specification of the above numbered patent requiring correction as follows: Page 2, line 3, claim 1, after the word "end" insert the words "below said plug to bear against the lower end"; and that the said Letters Patent should be read with this correction therein that the same may conform to the record of the case in the Patent Office.

Signed and sealed this 10th day of September, A. D. 1929.
